UNITED STATES PATENT OFFICE.

NATALIE SCHELL, OF NEW YORK, N. Y.

BOLT AND LOCKING DEVICE THEREFOR.

1,038,664.

Specification of Letters Patent. Patented Sept. 17, 1912.

Application filed September 22, 1910. Serial No. 583,179.

To all whom it may concern:

Be it known that I, NATALIE SCHELL, a citizen of the United States, residing at the city of New York, in the county of New York and State of New York, have invented certain new and useful Improvements in Bolts and Locking Devices Therefor, of which the following is a specification.

My present invention relates to an improved bolt and locking device therefor. Its manifold advantages will appear from an understanding of the following specification in connection with the drawings.

In the drawings which illustrate only one of the forms which my invention may take, Figure 1 is an elevation of a bolt and locking device or clip with my invention shown in use and as being applied to holding together a pair of objects in the form of plates shown in cross section; Fig. 2 is a top plan view of the devices of Fig. 1; Fig. 3 shows the bolt detached; Fig. 4 shows the locking clip detached, on a larger scale and in perspective; Fig. 5 shows a convenient method of manipulating a clip by the use of a pair of pincers; and Fig. 6 shows a slightly modified clip.

I will now describe the specific devices of the drawings, reserving it to the claims to point out the novel features and to define the scope of the invention, it being understood that the claims will be given due range of equivalents.

The bolt has a head 1 as usual. On the other hand, its shank is provided with one or more annular recesses 2.

The locking clip 3 consists of a piece of metal in U form having forks at its ends to straddle the shank of the bolt. It may be made of tempered sheet steel or other spring metal. The upper fork 4 straddles the bolt-shank in one of the annular recesses, whereas the lower fork 5 straddles the bolt-shank proper. The inner edges of the arms of the forks have recesses 4^a and 5^a which conform to the sides of the bolt-shank and due to the spring action of the arms of each fork toward each other the accidental withdrawal of the shank is prevented. Thus, in inserting each fork into straddling position, its arms are momentarily forced apart and then spring together into inclosing position on the bolt-shank when it has reached the recessed portions of the arms. The clefts 4^b and 5^b of the forks are shown extending

rearwardly beyond the recesses to give greater springiness to the arms. When in position, the clip is under more or less compression as desired, with its upper fork interlocking with one of the annular recesses 60 of the bolt-shank and with its lower fork delivering its thrust against the object and toward the bolt-head. The extent of this compression of the clip and of its resulting thrust depends upon which one of the annular recesses the operator chooses to receive 65 the upper fork. Naturally, the nearer the chosen annular recess is to the object, the more the clip must be compressed to insert it into position, and the greater will be its 70 thrust when in position. The ends of the fork-arms are bent upwardly. This facilitates the insertion of the clip into working position and in the case of the upper fork is a further safeguard against its accidental 75 disengagement from the bolt-shank. Thus, to insert the clip, its upper fork 4 is first partially, or even fully, inserted into the chosen annular recess. Then the lower fork is pressed downwardly against the object 80 and forwardly toward the bolt-shank into its final straddling position. The upturned ends of the fork-arms facilitate these manipulations. Finally, as shown at A in Fig. 1, the upturned ends of the upper fork-arms 85 oppose its accidental retraction by engaging the bolt-shank at the place indicated.

Means is shown on the clip to give a secure non-slipping grip to a pair of pincers in case such an instrument be used to manipulate it. Thus, an opening 6 is provided in the back of the clip and a transverse depression 7 is formed in said back leading to the opening. This permits the pincers to engage the clip as shown in Fig. 5.

In Fig. 6 the clip is shown embodying a modification. The opening 6 is omitted from the back of the clip so that the grip for the pincers is merely the transverse depression, groove or corrugation 7^a.

Having thus described my invention, what I claim is:

1. In combination, a bolt and a U-shaped spring metal clip, the bolt having an annular recess and the clip having forked ends, 105 one fork being inserted into straddling position in the annular recess and the other fork being inserted into straddling position on the bolt-shank next the object and there delivering the tension of the clip, the side- 110

- arms constituting at least one of the forks being resilient and coöperating with the bolt-shank to prevent its accidental withdrawal from the fork.
5. 2. In combination, a bolt having a recessed shank and a U-shaped spring metal clip having one end which detachably engages the recessed shank of the bolt and having its other end forked to straddle the bolt-shank next the object, the back of said clip being provided with an opening and a transverse groove leading thereto for engagement by a clip-operating instrument.
10. 3. In combination, a bolt and a permanently U-shaped spring metal clip instantly attachable and detachable at will from the bolt, the bolt being annularly recessed and each end of the clip having an open-mouthed fork, one fork being endwise insertible into straddling position in the annular recess and the other fork being endwise insertible into straddling position on the bolt shank next the object, and there delivering the tension of the clip, the extremities of the side arms of the forks being upturned, substantially as and for the purposes set forth.
15. 4. In combination, a bolt and a permanently U-shaped spring metal clip instantly attachable and detachable at will from the bolt, the bolt being annularly recessed and each end of the clip having an open-mouthed fork, one fork being endwise insertible into straddling position in the annular recess and the other fork being endwise insertible into straddling position on the bolt shank next the object, and there delivering the tension of the clip, the extremities of the side arms of the forks being upturned, substantially as and for the purposes set forth.
20. In testimony whereof I affix my signature in presence of two witnesses.

NATALIE SCHELL.
